METHOD OF AND APPARATUS FOR TREAT-
ING COTTONSEED LINTJohn C. Rogers and Redding Sims,
New Orleans, La.

Application July 6, 1938, Serial No. 217,784

6 Claims. (Cl. 19—156)

This invention relates generally to a system for removing cotton fiber from its seed, for handling the fiber, and the handling of air utilized in conveying the fiber.

- 5 Specifically, the invention relates to the removal of lint deposited on the screen of one or more condensers located adjacent a corresponding number of delinters or lint-removing machines.
- 10 It is an object of the invention to provide a coacting pneumatic lint and dust removal system wherein maximum removal of dust from the linters and condensers is assured as well as maximum removal of dust from the lint; and to generally improve the efficiency of systems of this type while at the same time simplifying and reducing the cost of initial installation and subsequent maintenance.

Another object of the invention is to provide 20 a fully automatic pneumatic system for cleaning, and conveying the lint to a baling press.

Another object of the invention is to provide for the efficient removal of dust-laden air from individual linter condensers and the recovery of 25 any fiber therein thereby preventing the escape of dust into the atmosphere of the delinting room, consequently decreasing health and fire hazards.

Another object is to subject the lint to a secondary cleaning and to recover any of the shorter fibers which may previously not have been recovered.

Another object of the invention is to provide a system in which the air containing dirt and 35 lint may be handled in such a manner that the cellulose content of the lint condensed may be varied within wide limits without discharging dirt and lint-laden air to the atmosphere.

Another object of the invention is to provide 40 means for producing a uniform grade of lint from two or more individual condensers.

Another object of the invention is to remove 45 condensed lint by aspiration and provide for inspection of the lint before such removal.

50 A further object of the invention is to provide an improved type of lint condenser wherein the lint is removed from the condenser screen through the medium of suction, thereby eliminating labor incident to the removal of lint from a bat roll or like device and at the same time effecting a cleaning action on the lint, and in conjunction therewith the removal of dust and dust-laden air blown through the condenser screen by the linter brush by improved dust-re-

moving means coacting with said suction or aspirating means.

A still further object is to improve the construction of the condenser screen to render such parts more efficient and durable, and to improve 5 lint condensers generally.

The foregoing and other objects and advantages will become apparent in view of the following description taken in conjunction with the drawings wherein:

Fig. 1 is a diagrammatic view illustrating one 10 application of the invention;

Fig. 2, a vertical section of an individual condenser in accordance with the present invention;

Fig. 3, a view in rear elevation and section 15 taken substantially on the line 3—3, Fig. 2;

Fig. 4, a vertical section of a portion of a linter and its coacting condenser, the latter in this instance having a modified form of air-removal duct; and,

Fig. 5, a fragmentary detail illustrating the 20 construction of a new type of screen for the condensers.

Referring to the drawings in detail, and first to Fig. 1, a battery of first cut linters is indicated 25 at 5 and a battery of second cut linters at 6. As will be understood, cottonseed with lint thereon is delivered to the first cut linters and lint is partially removed, after which the seed is taken by conveyor 7 to the battery of second cut linters 30 for a further delinting operation. At the rear of each of the first cut linters 5 is a condenser 8, the construction of which is shown more or less in detail in Figs. 2 to 4, inclusive, and will be subsequently described in connection with these figures. Lint from the individual condensers 8 is taken through a suction conduit or line 9 to a condenser 10, common to the said individual condensers, where a final condensing action of 35 the first cut lint is effected and from which the condensed lint may be taken to a baling press and baled. Dust and air from condenser 10 is taken through conduit 11 to a fan 22.

In the battery of second cut linters 6, lint and air are taken from the linters through take-off 45 conduits 13, which feed into a main trunk line 14 which delivers the lint and air to the condenser 12. In a similar manner dust and air pass through conduit 16 to the fan 22.

The dust control system is designed to coact 50 with the lint-removing and condensing system and includes conduit 15, which takes dust-laden air from the first cut condensers in a manner to be described and delivers it to conduit 16 beyond the condenser 12.

55

The lint from the condenser 12 is deposited in a bale press while the dust from all of the condensers is drawn through conduit 16 and then forced through conduit 17 to a collector 18, preferably of the cyclone type, from which it drops into a tailings beater 19. Dust and hull particles drop through the tailings beater into a hopper 20, while cleaned lint is drawn through conduit 21 back to the line 14 and thence to the second 10 cut condenser 12.

In operation, cotton seed is fed to the first cut linters in any suitable manner as through hoppers, not shown, and a portion of the lint removed and condensed in the individual condensers 8. As the lint is condensed or deposited on the screens of the individual condensers 8 it is aspirated or drawn therefrom in a manner to be described in conjunction with Figs. 2 to 4, inclusive, and delivered to the main first cut condenser 10. If a battery of second cut linters is to be used, they may be like the first cut condensers or of the conventional type of lint flue system as shown in Fig. 1. Seed from the first cut linters is taken by the conveyor 7 to the second cut linters, where the seed is subjected to a further delinting operation, the lint and air from the second cut linters passing to the main second cut condenser 12. Lint of first cut quality may, by this system, be kept separate from lint 30 of second cut quality.

Dust and dust-laden air is taken from the first cut condensers through the dust line 15, while at the same time dust is taken from the master first and second cut condensers 10 and 12 through 35 lines 11 and 16 respectively, line 11 tapping into line 16. Dust and lint-laden air from the entire system is conducted to the collector 18 and thence into tailings beater 19. When passing into the latter, all lint is removed from the hull particles 40 and progressed to a point where it is caught by suction and drawn through conduit 21 to the condenser 12.

Important advantageous features just described include:

45 The arrangement whereby a single fan 22 serves both the lint flue and dust control systems. By this means, not only is the cost of the original installation materially reduced, but subsequent maintenance costs are also reduced. 50 Furthermore, the installation as a whole is materially simplified.

55 By having individual condensers with each of the first cut linters instead of taking the lint and dust to a single main condenser, the character of the lint from each individual linter is open for ready inspection at all times. This is important, since where the lint is taken directly from a battery of linters to a single or main condenser, it often happens that the entire batch of lint is 60 lowered in quality due to an incorrect adjustment of a single linter. Thus, by observing the character of lint as it comes from each linter and before it mingles with the lint from other linters, the quality of the lint as a whole may be better regulated. As will be understood, the quality of 65 the lint is controlled at the delinting machine by adjusting the tonnage of seed passing through the machine in a given length of time and also by the degree of sharpness of the saws which remove the lint from the seed. While Fig. 1 illustrates a conventional lint flue system on the second cut linters, linters equipped like the first cut linters would have the same advantages as the first cut battery.

70 Dust separation is more easily handled at the

individual condensers than is the case where air and dust, or the air together with entrained lint and dirt is carried to a main or master condenser.

Aspiration or suction removal at each individual condenser reduces labor costs and ensures cleaner lint. 5

Waste or loss of lint is reduced to a minimum by the final stage of lint recovery, or the tailings beater 19 and by return of the recovered fiber 10 to the main condenser through the lint and air line 14. With the arrangement disclosed this added feature may be incorporated with a minimum initial cost and subsequent maintenance.

It may be desired to operate all linters on one 15 condenser and make only one cut of lint, in which case the tailing from the beater 19 would return to the suction main going to the master condenser.

Referring now to Figs. 2 to 5, inclusive, each 20 of the condensers 8 is preferably constructed in a manner such that the dust is removed by suction from the interior of the condenser drum, while simultaneously the lint is removed by suction from the exterior of the drum, or the drum 25 screen. This condenser may be considered in the nature of an improvement with respect to the condenser of our copending application Serial No. 132,079 filed March 20, 1937. The condenser, as shown, comprises a supporting base or frame 30 structure 23 on which is mounted a drum 24. This drum is free of all central obstructions such as the conventional central shaft with radiating spokes or spider members. In its preferred form the drum comprises a main foraminated backing 35 cylinder 25 which is preferably made of relatively heavy sheet metal formed with a plurality of perforations 26, said cylindrical body or backing member being connected at opposite ends to rings 27 formed with a smooth bearing portion 40 27a, internal gear teeth 28, and preferably also a peripheral flange 29. The cylindrical backing member or body 25 is clothed by a screen 30, which gives a friction surface to the foraminated cylinder, and smaller holes for screening surface. 45

With this type of drum, not only are all central obstructions obviated permitting unhindered installation of dust-removing means to be described, but also the conventional cross connecting ribs which form a backing for the screen are 50 eliminated. Furthermore, the backing cylinder 25 reduces wear on the screen due to the firm support afforded thereby. While in certain instances, it may be desirable to use a perforated 55 backing cylinder alone without the use of a screen, yet it has been found that in such instances the peripheral surface of the rigid backing member becomes smooth so that lint does not adhere thereto, resulting in loss of efficiency. Also, the elimination of ribs in condenser drums 60 permits a closer application of sealing strips which prevent the air from the linter brush from being blown out of or sucked into the confined area in the cylinder. The use of supporting ribs also necessitated the use of a flexible sealing 65 strip which would be subjected to fatigue by the reason of the fact that it was constantly being flexed by the ribs.

Each drum is mounted on a series of bearing rollers 31, which engage the smooth bearing portion 70 27a of ring 27, the drum being driven through the medium of a drive gear 33, which in turn is driven from a drive pulley 33a, connected to a line shaft or any other suitable source of power. The bearing rollers 31 are supported 75

through the medium of bracket 35, which in turn is supported on cross frame member 36.

In this connection, there are certain advantages inherent in the placing of the teeth inside 5 of the end rings of the drum. For example, there is no chance for the lint to collect on the teeth which would be the case where they are maintained on the periphery of the drum oftentimes resulting in clogging and defective operation.

10 Lint from the linting machine is blown by the revolving linter brush B, note Fig. 4, against a sealed-off or active portion of the drum 24, or the screen 30 thereon, through conduit 37. The means for sealing off the active portion of the 15 screen on the interior of the drum comprising a sealing plate 38 mounted inside the drum and provided at its lower extremity with a suction conduit 39, having an intake slot 40, or in the modified construction of Fig. 4 with a section 20 conduit 39' having an intake slot 40'.

The difference in the modified construction is in flaring the suction conduit toward its discharge end, or having it of megaphone shape, to obtain 25 more capacity for the air, which increases in amount as the discharge end of the conduit is approached.

It will be noted that the conduits 39 and 39' are located at a point below the area set off by said 30 plate 38. This is a distinct advantage in that all dust particles automatically gravitate to the conduits 39 and 39', thereby permitting more efficient removal with relatively low suction not only at each individual condenser but throughout the 35 entire system. The conduit 37 forms an enclosed chamber on the outside of the condenser screen and the plate 38 forms a corresponding chamber on the inside of the screen with the active portion of the screen forming a partition between the chambers. Thus practically the total amount 40 or volume of air in the outer chamber is exposed to the active surface of the screen and may pass therethrough.

It will further be noted that suction applied 45 to the duct at the interior of the condenser screen is communicated to the inner side of the screen, so that an auxiliary suction action is applied to remove from one side of the screen the air, dirt and fiber blown to the other side of the screen by the linter brush.

50 To effect removal of the lint from the exterior of the screen, an aspirator 41 is provided and is mounted with its flared nozzle end lying closely adjacent the surface of the screen. This aspirator is superior to the conventional bat roll in that 55 it eliminates the labor incident to removal of the roll and bat and replacement of the empty roll; it affords an additional cleaning of the lint; it is readily adapted to the dust system heretofore described, and has other points of superiority with 60 respect to the bat roll system.

If desired, conventional holders may be employed for receiving the conventional bat roll, not shown. Such holders may be provided in the 65 event it is desired to use conventional rollers in place of the aspirator for removing lint from the screen 30.

It should be noted that the type of backing for 70 the condenser screen as herein disclosed is particularly adapted for use with an aspirator or suction removal system, since the screen is rendered perfectly symmetrical throughout its circumferential area. In other words, the periphery of the screen is even and is devoid of any irregularities which would be the case if the 75 screen were supported by ribs or analogous means.

By having an efficient dust removal system as herein disclosed, the condenser screen may be rotated at a speed such as will result in a relatively thin film of lint deposited thereon, thereby obtaining maximum efficiency in dust removal from 5 the lint. This is of considerable advantage over systems wherein the dust and dirt is blown out into the linter room, since in such cases there is a tendency to build up a relatively thick layer of 10 lint on the condenser screen in order to reduce the amount of dust and dirt discharged into the room. Since the cellulose content of the lint is directly proportional to the purity thereof, or is 15 reduced in proportion to the amount of dirt in the lint, a more efficient cleaning action results in a higher quality product.

With applicants' dust-control method on a first cut linter the shorter fibers are, to a considerable extent at least, actually pulled through the condenser screen together with the dust and dirt so 20 that the first cut lint is cleaner and of longer staple and therefore commands a higher price. The shorter fibers from the first cut linter then go with the staple taken off from the second cut linter or linters and which second cut lint is sub- 25 stantially identical with that drawn through the condenser screens of the first cut linters. Therefore this mixing of the short fibers from the first cut lint with those of the second cut lint does not lower the value of the second cut lint, the latter 30 usually being sold upon the cellulose content thereof and which is not dependent upon the length of the staple. The first cut lint derives its value primarily from the length of the staple and its cleanliness. 35

It will be understood that the system illustrated may be changed and rearranged as well as certain parts omitted while still retaining the teachings of the invention, and also that certain changes in construction and design of the condenser unit 40 may be made within the province of the invention as defined by the appended claims.

We claim:

1. In a system for delinting cottonseed, a battery of first cut linters and a battery of second cut 45 linters, individual condensers operatively associated with certain of said linters and provided with condenser screens, an aspirator operatively associated with each of said screens for removing lint therefrom by suction, a condenser common to said individual condensers and another condenser common to said second cut linters, separate suction conduits for conveying lint from said condensers and said linters to said main condensers, a separate suction line for removing dust 55 from said individual condensers without passing it through the screens of said main condensers, a cyclone collector and a tailings beater operatively associated with said collector, a return conduit providing a pneumatic conveyor for returning lint 60 taken from the dust and hull particles by said tailings beater to the main system, and a fan common to said lint-conveying and dust-removing means for establishing pressure in the system.

2. In a system for delinting cottonseed, a plurality of linters, individual condensers for at least a portion of said linters each having a hollow condenser screen, means removing lint by aspiration from said condenser screens, the system including a suction conduit operating to convey lint from 70 said linters to a point of deposit or for further treatment, means for simultaneously removing dust and dust-laden air from the interior of said individual condenser screens, means for separating lint from said dust-laden air, a dust flue com- 75

- mon to said dust removing means operating to convey the dust and dust-laden air to said separating means without mixing the dust with the lint from the linters or from the individual condensers, and means for returning the lint reclaimed from the dust to said lint-conveying means.
3. In a system for delinting cottonseed, a plurality of linters each of which has a linter brush, individual condensers for at least a portion of said linters each having a hollow condenser screen on which lint is blown by said brush, means removing lint by aspiration directly from the periphery of each individual condenser screen, a main condenser common to at least a portion of said linters, the system including a suction conduit operating to convey lint from said linters to said main condenser, means removing dust and dust-laden air by suction from the interior of said individual condenser screens, a dust flue common to said dust removing means but separate from said lint flue, means for separating lint from the dust-laden air, said dust flue communicating with said separating means, and means for returning the lint reclaimed from the dust to said lint flue.
4. In a system for delinting cottonseed, the method which consists in subjecting the seed to first and second cut delinting operations, applying suction to the interior of a condenser screen of a first cut lint condenser to remove from the inner side of the screen the air, dirt and fiber deposited on the exterior of the screen and passing therethrough, removing the fibers deposited on the exterior of the screen, and mixing the shorter fibers pulled through the screen with other fibers obtained as a result of the second cut delinting operation.
5. In a system for delinting cottonseed, a first cut linter and a second cut linter, a condenser associated with the first cut linter and having a revolving condenser screen, means for blowing lint to the exterior of said screen, a suction conduit communicating with the interior of said screen and operating to remove from the inner side of the screen the air, dirt and fiber which passes through the screen, and means for conducting the short fiber passing through said screen and into said suction conduit with the fiber obtained by said second cut linter.
6. In a system for delinting cottonseed, a battery of first cut linters and a battery of second cut linters, individual condensers operatively associated with certain of said linters and provided with condenser screens, individual aspirators operatively associated with the peripheries of said screens for removing lint directly therefrom by suction, a main condenser for first cut lint and a separate main condenser for second cut lint, a lint conveyor suction conduit communicating said aspirators with said first cut condenser and another conveyor suction conduit communicating said second cut linters with said second cut condenser, suction members arranged to remove dust and dust-laden air from the interior of said condenser screens and a main dust conduit or line common to said suction members, a collector arranged to receive dust, hull particles and the like from the system, said dust conduit or line being arranged to convey dust and other matter from said individual condenser screens to said collector without passing it through the screens of said main condensers.

JOHN C. ROGERS.
